ATTORNEYS

UNITED STATES PATENT OFFICE.

OSCAR W. OLSEN, OF PHILADELPHIA, PENNSYLVANIA, ASSIGNOR OF ONE-FOURTH TO WILLIAM S. ADAMS AND ONE-FOURTH TO D. CLARENCE GIBBONEY, BOTH OF PHILADELPHIA, PENNSYLVANIA, AND ONE-FOURTH TO HARRY N. BUTLER, OF BROOKLYN, NEW YORK.

IDENTIFICATION MEANS AND METHOD.

1,372,036.

Specification of Letters Patent. Patented Mar. 22, 1921.

Application filed February 6, 1920. Serial No. 356,643.

To all whom it may concern:

Be it known that I, OSCAR W. OLSEN, a citizen of the United States, and a resident of the city of Philadelphia, county of Philadelphia, and State of Pennsylvania, have invented certain new and useful improvements in Identification Means and Methods, of which the following is a specification, reference being had to the accompanying drawing, forming a part thereof.

The invention relates to an identification device and the secret placing of it in certain movable objects, some of which are herein-after mentioned, so that it cannot be destroyed and enabling the owner to positively identify his property when it has been taken from his possession.

The very frequent theft of automobiles has made it necessary to devise some means whereby a stolen automobile may be readily identified. The identification marks heretofore utilized on automobiles, as for example, by casting a number in the engine casting, or securing a stamped plate to the automobile body, are open to view and are easily destroyed or modified by the thief to avoid identification.

An object of my invention, therefore, is to provide an identification means or device that may be concealed in any suitable part of the vehicle in such a manner that it would be practically impossible for any one, particularly a thief, to locate the same. It is also an object of my invention that the identifying device comprise identification data, and that a record thereof be secretly kept, as by an insurance company insuring the automobile, so that in the event of the theft of an automobile, the records may be referred to by a proper officer of the insurance company, who, following such record, may locate the concealed spot where it is believed the identifying device may be placed in order to determine whether or not the automobile suspected of theft is in fact the one sought for.

Other objects of my invention will appear more fully in the following specification and from the drawing.

One manner of employing my invention is illustrated in the drawing, in which Figure 1 is a view partly in section of a part of an automobile; Fig. 2 is a longitudinal section

of a capsule including the identification data; Fig. 3 is an illustration of the sheet of paper containing the identification matter; and Fig. 4 is a transverse section taken on the line 4—4 of Fig. 2.

Referring more particularly to the drawing in which similar reference characters are used to designate the corresponding parts of the several views, I have shown parts of an automobile representative of any part that may be selected for the purpose desired, and in the illustration shown, the parts comprise a door 1 provided at its lower edge with a cross piece or sill 2 adapted to close over the body sill 3 of the automobile. Beneath the sill 3 and secured thereto, in any suitable manner, is the chassis 4, from which may be supported the bracket 5 secured to the chassis by means of rivets 6. Upon the free end 7 of the bracket may be supported a running board 8 secured to the end 7 by means of bolts 9 and 10 in the usual manner. These parts are selected mainly for the purpose of illustration, but I do not consider myself limited to the selection of these particular parts, as any part of an automobile, as for example, parts of the engine, transmission, differential, or other permanent parts of the vehicle, such as the body, frame, steering post, and so on.

My invention relates more particularly to a provision of a recess or recesses in any selected or suitable part of the automobile, such as the recess 11, 12, or 13, respectively located in the sill 2 of the door, the body sill 3, and the bolt 9. In one or more of these recesses I locate or insert a capsule 14 which may be of the usual gelatin composition, although such capsule may be made of any other material, such as metal, compositions, or the like. In the capsule I place a roll of paper 15 upon which is entered the identification data, such as is shown in Fig. 3 of the drawing. After locating the capsule in the recess, I may then insert packing material 16, of a fibrous nature, such as cotton, or the like, and I then close or conceal the opening of the recess with a moldable sealing substance or material 17, such as "smooth-on," composed of putty, iron filings, and a suitable substance that will permit the same to harden and set in place, as well as a suitable coloring matter, and which also may be

given a smooth surface finish substantially identical to the surface surrounding the opening of the recess. After the recess is sealed in the manner above indicated, the 5 surface may then be suitably coated, colored, or otherwise treated, so that the particular spot where the recess is located may not be distinguished from the surrounding surface of the part in which the recess is provided. 10 In this way it will be impossible for any one, not knowing the exact point where the recess is located, to locate the same and change the identification data inserted therein.

While I have illustrated one form of my 15 invention and the manner in which I may employ the same, it is to be understood that I do not consider the same limited to the particular details illustrated, but that the identifying device above described may be 20 located in any part of the automobile, as for example, recesses may be bored or drilled in the metal parts of the engine, the magneto, in the steering post, in the steering wheel, in the supporting brackets for the wind shield, 25 in the transmission casing, in the spokes of the wheel, or any part desired. It is, of course, intended that no two automobiles will have the same points of location for the identification device. By my invention the 30 scheme will be followed by providing each automobile with entirely different points of concealment for the identification device, and records thereof kept in the secret 35 archives of the insurance company, one of the officers in the insurance company selecting the point of concealment for placing therein the identification device without disclosure to any other person regarding the exact position where the particular device 40 is placed, in a particular automobile. As, for example, the record may indicate the name and make of the automobile, its owner, date of sale or transfer, and the exact spot or spots where the identification device or 45 devices may be found in that particular automobile. Such indication may be made, as for example, as follows: so many inches from the lower hinge of the right hand forward door and midway the thickness of the 50 lower sill thereof, or so many feet and inches from the rear end of the body sill and midway the thickness thereof, or the second inner bolt from the rear end of the running board and in the lower end of said bolt.

55 When an automobile is stolen and reference is made to the records of the insurance company for that particular make and type of car, the record will indicate that the identification data of that automobile will be 60 located in the particular spot as indicated above, and if a car of the type mentioned is found and inspected, the proper officer of the insurance company may locate the point of concealment in the manner above indicated,

and with a prick punch, break the sealing 65 material 17 and access to the recess may be had for the purpose of extracting the capsule 15 containing the desired data sheet. It may be also convenient to provide not only a single identifying means in each car, but 70 also any number in different points so that if the ingenuity of the thief is such that if he find one identifying device, either by accident or otherwise, the chance of his finding the others will be extremely small and 75 remote, and the provision of two or more points of concealment would aid in insuring against successful theft.

While I have disclosed my invention with particular reference to an automobile, it is 80 to be understood, however, that my invention may be of equal utility for identifying other movable objects, such as boats, launches, aeroplanes, machinery, trunks, hand baggage, and similar objects. It is 85 also to be understood that I do not consider the same limited to the particular details illustrated in the accompanying drawing and described herein, but that other forms and methods of carrying the same out may 90 be adopted without departure from the spirit of the invention and the scope of the appended claims.

Having thus described my invention, what I claim and desire to protect by Letters Pat- 95 ent of the United States is:

1. The combination with a part of an automobile provided with a small recess therein, of a capsule placed in said recess, identifying data inclosed within said capsule, cotton or similar fibrous material packed in said recess between the opening of said recess and said capsule, and moldable substance hermetically closing said opening flush with the surface of said part, 100 and having an outer surface matching the surface surrounding said opening.

2. The method of concealing identifying data in an automobile, which consists in providing a part of the body of an automobile with a small recess, placing an identification sheet in a capsule, inserting said capsule in said recess, inserting yieldable packing material in said recess against said capsule, then hermetically closing the opening with 115 sealing material, and providing the same with a smooth surface flush with and of a color to match the surrounding surface of said part.

3. The combination with any suitable 120 part of an automobile provided with a recess, of means for identifying said automobile placed in said recess, comprising a capsule and means having identification data in said capsule, packing material in said re- 125 cess for maintaining said capsule from relative movement, and sealing material completely closing said recess, said sealing ma-

terial being provided with a surface having a finish similar to that of the surface surrounding said recess.

4. The combination with any suitable part of an automobile provided with a recess, of a device for identifying said automobile placed in said recess, comprising a small container, means having identification data in said container, fibrous packing in said container for maintaining said container from relative movement, sealing material for hermetically sealing said recess, said sealing material being provided with a surface similar in finish to the surface surrounding said recess.

5. A device for identifying an automobile comprising a capsule, containing a roll of

paper upon which identification data are placed, inserted and sealed in a secreted recess provided in any suitable part of an automobile, packing material in said recess for maintaining said capsule from relative movement, and a moldable substance, adapted to set and harden, sealing the opening of said recess and concealing said capsule, packing material and recess, said sealing substance being provided with a surface finish substantially with that of the material surrounding said recess for completely concealing the location of said device.

In witness whereof, I have hereunto set my hand this 5th day of February, 1920.

OSCAR W. OLSEN.
